UNITED STATES PATENT OFFICE.

CHARLES MEHLIN, OF FORT LEE, NEW JERSEY.

PIANO CONSTRUCTION.

Application filed August 3, 1923. Serial No. 655,423.

This invention relates to piano construction and has more particular reference to the sounding board and bridge arrangement.

5 In the ordinary piano construction the plane of the sounding board and the plane or planes in which the strings lie are parallel and the bridge of the treble and middle strings and the bridge of the bass strings 10 are each of uniform height from end to end.

A principal object of the present invention is the provision of a piano in which the bridge and sound board construction and arrangement will provide a varying height 15 of bridge for the strings, the bridges increasing in height as the length of the strings increase and at the same time maintaining each string substantially in parallelism with the sound board. That is to say, 20 each string, particularly the treble and middle strings and only slightly less of the bass, is arranged at substantially an equal distance from the sound board throughout its length and the distance of each string 25 from the sounding board is best calculated to give maximum purity and evenness of tone quality. This is accomplished in the instance selected for the purpose of illustration and hereinafter described in detail 30 by providing bridges of increasing height from right to left across the piano and arranging the sound board in a plane divergent from the plane of the strings crosswise of the piano as will be better understood 35 from the following description, which, taken in connection with the accompanying drawings, discloses a preferred embodiment thereof.

Referring to the drawings,

40 Figure 1 is a top plan view of so much of a grand piano constructed in accordance with my invention as is necessary to an understanding thereof;

45 Fig. 2 is a partial section through the keyboard showing one of the strings of a group, the key action and

50 Figs. 3, 4 and 5 are sections taken respectively on the lines 3—3, 4—4 and 5—5 of Fig. 1.

55 In the piano construction shown on the drawing for the purposes of illustrating my present invention reference character 11 designates an outer rim forming to the shape of the piano, reference character 12 an inner rim, and reference character 13 the

key bottom. Reference character 14 indicates the usual action which need not be described in detail since it has no particular reference to the present invention. The usual iron plate is indicated at 15 and the 60 sounding board is indicated at 16.

Upon the sounding board two bridges 17 and 18 are provided, the bridge 17 being engaged by the treble strings 19 and middle strings 21 and the bridge 18 by the bass 65 strings 22. The strings are fastened at the end remote from the keyboard to hitch pins 23 and 24 on the metal plate and to wrist pins 25 at the front in the usual manner. The bridge 17 increases in height from the 70 end carrying the short or high pitch strings to the end carrying the long or low pitch strings (Fig. 1) and the same is true of the bridge 18.

In the illustration shown on the drawing the strings are arranged in horizontal planes and to accommodate these increases in height of the bridges the sounding board is arranged farther from the strings at the left side of the piano than at the right, i. e. 80 (viewing Fig. 1) the sounding board diverges from the planes of these strings from the lower portion of this figure toward its top. The sounding board is supported upon the inner rim 12, which decreases in 85 height from the right around to the left of the piano as may be seen in Figs. 3 and 4 and corresponding increases in the height of the blocks 26 which support the iron plate 15. By reason of the decreased thickness of 90 the inner rim 12 at the left of the piano it should be made of increased thickness. The sounding board is supported at the front or keyboard side of the piano by the usual rail 27 and cross block 28, which in the present instance also decrease in height to permit the sound board to tilt across the piano front as it does at the back of the piano. 95

It will be manifest that the strings are as nearly parallel throughout their length 100 with an element of the sound board as their slight angular relation with each other permit and that each is in substantial parallelism throughout its length with the sound board.

105 While the invention has been hereinbefore described as incorporated in a grand piano, it can, of course with equal facility be used in an upright piano and it will be manifest that various changes may be made 110

in the form, construction and arrangement of the parts without departing from the spirit and scope of the invention or sacrificing all of its material advantages, the form 5 hereinbefore described being merely a preferred embodiment thereof.

I claim:

1. A piano having strings of different length and its sounding board fixed in a 10 plane diverging from the plane of the strings in the general direction transversely of the strings, whereby the strings are arranged substantially parallel throughout their length with the sounding board and 15 at increasing distances therefrom as the lengths increase.
2. A piano having strings of different length, and a sounding board fixed in a 20 plane providing substantial parallelism between each string and said sounding board, the strings of longer length being farther from the sounding board than the strings of shorter length.
3. A piano having a single string plate 25 for all of the strings, and a sounding board fixed in a plane angularly arranged with

the plane of the strings and diverging therefrom transversely of the piano.

4. A piano having a series of strings, and a sounding board fixed in a plane diverging 30 from said string in a general direction across the strings, and a bridge interposed between the strings and the sounding board and increasing in height from the shorter strings to the longer strings. 35

5. A piano having a string plate, a series of wrist pins, a curved series of hitch pins, a sounding board, the string plate and the sounding board diverging at the wrist pin and hitch pin sides of the piano, and a 40 bridge following generally the curve of a series of hitch pins and increasing in height from the shorter strings to the longer strings.

6. A piano having a single string plate 45 for all of the strings, a bridge increasing in height as the strings increase in length, and a sounding board fixed in a plane angularly arranged with the plane of the strings and diverging therefrom transversely of the piano. 50

CHARLES MEHLIN.
